UNITED STATES PATENT OFFICE.

ELI J. BLAKE, OF BUFFALO, NEW YORK, ASSIGNOR TO GOULD COUPLER COMPANY, A CORPORATION OF NEW YORK.

ELECTRIC REGULATION.

Application filed March 25, 1922. Serial No. 546,852.

To all whom it may concern:

Be it known that I, ELI J. BLAKE, a citizen of the United States, and resident of Buffalo, in the county of Erie and State of New York, have invented certain new and useful Improvements in Electric Regulations, of which the following is a specification.

The invention relates to electric regulation, and particularly to lamp regulators, or regulators for other loads, in which current is received from a source having a widely varying potential. The invention is particularly adapted to meet conditions involved in maintaining lamp voltage on multiple unit cars receiving current from a third rail at a voltage which varies between 350 and 750 volts. In such a case the energy dissipation required is much greater than that required in usual practice in connection with lamp regulators, operating on 30 or 60 volt circuits, and the resistance range which would be required of a carbon pile is considerably in excess of the resistance range ordinarily required.

In order to meet such conditions, in accordance with the present invention, circuits are arranged in which the greater part of the duty of energy dissipation is placed on fixed resistance units, which are preferably used in connection with unusually long piles of carbons of small diameter.

The invention involves combinations and arrangements of circuits, resistances, and controlling means therefor by which the desired regulation may be accomplished, and also involves certain features of mechanical construction. Among these latter may be mentioned improved means for controlling the pressure on carbon piles of a character particularly adapted for use in this invention. Experience has shown that friction of the pile prevents adequate release of pressure through a pile of considerable length when such release is effected by movement of one end only. Accordingly a feature of this invention comprises the provision of movable heads at both ends of a pile, with the further provision, when a plurality of piles are used, of an equalizing system arranged to maintain the same pressure on the ends of all the piles.

Generally speaking the objects of the invention are, first, the provision of means for dissipating a relatively large amount of energy for the purpose of regulation without the necessity of providing a proportionate dissipating capacity in the regulating carbon pile; second, the provision of means whereby the sensitiveness of regulator action may be increased by increasing the variation of the regulating current produced by a given change in the load circuit; and third, the provision of effective mechanism for the simultaneous control of a plurality of carbon piles. Other objects of the invention comprise the provision of improved combinations of parts and construction of elements as will be more fully set forth in the following specification.

In order that the invention may be more clearly understood, attention is hereby directed to the accompanying drawings forming part of this application and illustrating certain embodiments of the invention. In the drawings—

Fig. 1 represents a front view partly in section of a regulator comprising features of the invention;

Figs. 2 and 3 are vertical sections taken respectively on line 2—2 and line 3—3 of Fig. 1, and

Figs. 4 to 10 inclusive are circuit diagrams illustrating various manners in which the invention may be applied.

Referring first to Figs. 4 to 10 of the drawings, various systems or circuit arrangements are diagrammed in which the first and second of the three above named general objects are provided for. The mechanical constructions by which the third object is effected will be explained later in connection with Figs. 1 to 3 of the drawings.

Fig. 4 illustrates a case in which it is desired to maintain a constant current in the load, indicated as a single lamp 3. The fixed resistance 1 and the carbon pile 2, comprising a variable resistance composed of a plurality of contacting electrodes, controlled by solenoid 4, are connected in parallel with each other and in series with the lamp 3. At 5 is indicated a ballast resistance having a constant current characteristic connected

in parallel with the solenoid 4. The circuit is controlled by a switch 6 and is supplied with energy from a variable potential source which is not illustrated but is indicated merely by the symbols plus and minus at the ends of the circuit.

It will be noted that the multiple group consisting of the solenoid 4 and the ballast resistance 5 is connected in series with the 10 load. If the current in the load circuit increases as the supply potential varies, the current through the solenoid will increase until it reaches such a value as to relieve the carbon pile 2 of pressure, thereby increasing 15 the resistance in series with the load, and tending to limit the load to a definite value determined by the characteristics of the solenoid 4.

It is well known that certain conductors 20 such as iron wire at a critical temperature value have the characteristic that their resistance increases very rapidly with their temperature and consequently with the current flowing through them. The result is 25 that they maintain a very close approximation to a constant current flow throughout a considerable range of voltage variation across their terminals. The ballast resistance 5 has this characteristic; consequently 30 the current which flows through it is nearly invariable, and practically the whole variation of current through the load 3 is provided by a variation of the current through the solenoid 4. The variation of current in 35 the solenoid being the total variation, while the total current in the solenoid is only a fraction of the total load current, it is evident that a given percentage variation in load current will produce a larger percentage 40 variation of current through the solenoid 4. For example, if the ballast resistance 5 maintains a constant current of 8 amperes, and if the solenoid 4 is designed to regulate at 2 amperes, the solenoid will 45 receive its normal current when the load circuit is receiving 10 amperes. If now, the load current is diminished to $8\frac{1}{2}$ amperes, or 85% normal, the current in the regulating coil will be reduced to 0.5 ampere or $\frac{1}{4}$ 50 of its normal value. In like manner any variation of current in the load circuit 3 will produce a relatively magnified variation of current through the regulating solenoid 4 and a correspondingly magnified regulating 55 action.

In the example illustrated by Fig. 4, it will be assumed that load or translating means 3, in which a constant current is to be maintained, has constant resistance and 60 that the potential drop through lamp 3 will also be constant. Neglecting the small drop of potential through solenoid 4 and ballast resistance 5, it is evident that the parallel circuit consisting of the resistor 1 and 65 the carbon pile 2 must absorb a variable

amount of energy depending upon the difference between the variable supply voltage and the constant load voltage. The current being constant, the energy absorption is maximum when the voltage drop is a maximum. At this time we may assume for purposes of illustration that the carbon pile has been so far relieved of pressure that the current through it is negligible. The total current will then flow through a fixed resistor 1, the resistance of which must not be less than the total resistance required for the maximum drop of potential. Under this condition the energy dissipation in carbon pile 2 is zero, but as the required drop diminishes the current supplied by the fixed resistor becomes insufficient to maintain the required constant current in the load. The solenoid 4 accordingly permits an increasing compression of the carbon pile 2 which supplies an increasing share of the current required for the load circuit. At the same time the voltage across the pile and the fixed resistor decreases. The maximum watts dissipation in the pile occurs when the pile is supplying one-half of the total load current at one-half of the maximum potential drop. Hence the duty of the carbon pile in watts is one-quarter as great as the duty it would perform at the maximum drop, if the fixed resistor were absent.

The circuit shown in Fig. 5 is similar to that just described, except that the solenoid 4 and its shunt ballast resistance 5 are connected across the terminals of the load 3, (in series with a resistor 10) and, therefore, act to maintain constant potential on the load circuit, whereas in Fig. 4 the solenoid 4 with its shunt ballast resistance 5 was connected in series with the load circuit to maintain constant current in that circuit. It will, of course, be understood that the solenoid and the ballast resistor shown in Fig. 5 will be of finer wire and will be given suitable characteristics in each case for the circuit with which they are to be used.

The circuit shown in Fig. 6 is similar to that shown in Fig. 5, but instead of a constant lamp load, the load is shown as consisting of three branch circuits, each containing a lamp 3, these branch circuits being controlled by separate switches 8. Also instead of a single fixed resistor, as shown in Fig. 5, the fixed resistor element is divided into two portions 1¹ and 1², arranged for parallel connection. The fixed resistor element 1¹ is connected in parallel with the carbon pile 2 by a series relay 7 when the current in the circuit exceeds some prescribed value such for example as 10 amperes. In like manner the resistor section 1² is cut in by the relay 7¹ when the load current exceeds some higher value such as 20 amperes. In either case the resistance actually connected is so proportioned to the

connected load as to function substantially in the manner described in connection with Figures 4 and 5, that is to say, the resistance in parallel with the carbon pile at any given load is approximately the resistance required to supply a major part of the load current when the supply potential is a maximum. In this example, as in that shown by Fig. 5, the solenoid 4 with its shunt ballast resistance 5 (and series resistor 10) are connected across the load terminals to maintain constant potential on the load circuit.

In Fig. 7 a similar circuit is shown in which, however, the relays 7^a and 7^b are associated, each with an individual branch of the load circuit. Whenever current flows in one of the load circuits, such as the upper one shown in the figure, the relay, such as relay 7^a, closes so as to connect the carbon pile and a resistor suitable for that particular load circuit in parallel. When, for example, the switch 8 of the upper load circuit is closed, the resistor 1^a and pile 2 will be connected in parallel by the closing of relay 7^a, and when switch 8 of the lower load circuit is closed the other fixed resistor 1^b will be cut in by the relay 7^b.

The arrangement shown by Fig. 8 is similar to that shown in Fig. 7 with the exception that the shunt resistance around the carbon pile is varied by short circuiting a section for each load circuit cut in, instead of by adding a resistor in parallel. The connections by which sections of resistor 1^c are thus affected will be apparent from the diagram.

The arrangement shown in Fig. 9 is similar to that shown in Fig. 7 with the exception that the resistor for each load circuit is cut in by a switch, upon closing the circuit, instead of by a relay. For example, if the load circuit 3^b is closed by closing the double pole switch 8^b, the resistance section 1^b is simultaneously connected to the line in parallel with carbon pile 2.

Fig. 10 illustrates what may be considered an elaboration of the system shown in Fig. 7. In the system shown in Fig. 10 four load circuits are provided for, each being shown as comprising five translating devices, such as lamps 3, in series. Resistors 1^a, 1^b, 1^c, and 1^d are shown as permanently connected in series, each with one of the lamp circuits, these resistors being suitable for absorbing the difference between the maximum supply voltage and the lamp voltage. Relays 7^a, 7^b, 7^c and 7^d are arranged similarly to the relays 7^a and 7^b in Fig. 7, one of these relays closing whenever its lamp circuit is energized, and connecting the mid point between the lamps and the corresponding resistor to a bus connection 21¹ leading to the regulator carbon pile 2. The ballast resistance 5 is shown in shunt with coil 4, as in the previously described diagrams.

It will be noted that a resistance unit 10 is in series with regulating coil 4. Resistance 10 has three functions; first to absorb a portion of the load voltage, which in the case of an installation such as is illustrated in Fig. 10, may be too high for satisfactory application directly to coil 4. Second, to permit the coil to be wound for relatively small voltage and high current. This is for the purpose of assuring a certain minimum current flow through the carbon pile, even when all load circuits are open. This minimum current flow being assured, it is not necessary to reduce the current through the pile to zero, and any opening of the circuit in the pile with an attending tendency to vibration is avoided. Third, the series resistance unit 10 may be of very low temperature coefficient and may serve to limit the variation of regulator setting, due to variation of resistance with temperature in the regulating circuit.

It will be understood that the constant current ballast resistance may be used in various installations for the purpose of increasing the sensitiveness of the regulating action, and that the use of the same constitutes one of the features of the invention, but that the invention is not limited to include this feature, and that the same may sometimes be omitted.

Figs. 1, 2 and 3 illustrate a form of regulator in which the systems of regulation above described may be carried out and in which an improved mechanism for the control of the carbon piles is effected. The regulator, as shown, may be considered as applied to the regulating system diagrammatically illustrated in Fig. 10, it being, of course, understood that the connections may be modified to meet desired conditions in accordance, for example, with the other forms of regulation referred to in connection with the other diagrammatic views which have been described.

Referring to Figs. 1, 2 and 3, it may be noted first that a series of carbon piles 2^a, 2^b, 2^c, and 2^d are used which may be long piles of carbons of small diameter connected together in series and which will correspond to the carbon pile 2 referred to in the various wiring diagrams. Pressure on opposite ends of all these piles is equalized and controlled by means of mechanism to be described. In place of the regulating coil 4 referred to in connection with the various diagrams Figs. 4 to 10, a pair of regulating coils 4¹ and 4² are illustrated which are provided with cores having poles between which an armature is adapted to swing, the movement of the armature serving to control the pressure on the carbon piles by means to be described.

Referring now in detail to the construction illustrated, a pair of brackets 11 and 12

12 are provided for attachment to the underside of a car floor. Within the bracket 12 is formed an outlet 12^a for connection to a conduit system through which wires pass 5 between the wiring system of the car and the regulator. A frame 14 is attached by bolts 13 to the brackets 11 and 12, and a sheet metal cover 15 is illustrated as clamped between the brackets and the frame, this cover 10 forming the top of the enclosing case 16. The latter may be suspended by a hinge 17 from the bracket 12 and by a latch (not shown) from the bracket 11.

In Figs. 2 and 3 tubular resistance units 15 1 are shown, these corresponding to the fixed resistors 1, 1^a, 1^b, etc., described in connection with the diagrams Figs. 4 to 10. A tubular resistor 10 is also indicated, this corresponding to the resistance 10 already described in connection with Fig. 10. All of these resistors, namely four of the resistors, 1, and the resistor 10, are shown as mounted on rods 18 which extend between a flange, at the left hand end of the frame 14, and a strap 19 near the right hand end of the regulator. At the right hand end in Fig. 1 the resistors 1 are connected to studs 20 mounted in a slate panel 101.

The relays 7^a, 7^b, 7^c and 7^d, corresponding 20 to the relays having the same designations shown in Fig. 10, are also mounted on panel 101. Each one of the studs 20, connected to one of the resistors 1, also forms one terminal of the corresponding relay 7^a, 7^b etc., the 25 opposite terminals of these relays being shown at 21. Terminals 22, as indicated, are provided for incoming wires which may extend from four lamp circuits in the car corresponding to the four lamp circuits indicated in Fig. 10. Terminal 23 is provided for a connection leading from the positive supply main. Terminal 23 is adapted to be connected through the resistor 10 to the regulator coils 4 and so back to the terminal 24 which is connected by the bus bar 21¹ to the various terminals 21 of relays 7^a, 7^b, etc. A ballast resistance lamp 5 is connected in shunt around the regulator coils 4^a, 4^b. From the terminal 24 a circuit passes 30 through the carbon piles 2^a, 2^b, 2^c and 2^d in the order named to a ground connection 25 on a frame 14. This circuit will be traced later.

Contact with each carbon pile is made at 35 each end of the same through plungers 26, 26, each of which bears at one end against the carbon pile. The other ends of the plungers 26 at the left hand ends of the piles, referring to Fig. 1, bear against equalizing levers 27. At the right hand ends of the piles plungers 26 of piles 2^b and 2^c bear against a similar equalizing lever 27, while plungers 26 at the right hand ends of piles 2^a and 2^d bear against terminal blocks 28. 40 A light spring 29 is positioned around each

plunger 26 and bears against a washer and cotter pin 30 at one end and against the cap 31 of the pile at the other end to maintain a slight contact pressure between the plunger and the equalizing lever 27 or contact 70 block 28, even though the carbon pile be completely relieved of pressure.

As indicated, each carbon pile assembly includes a tubular housing 31, supported by clamps 32 from bosses 33 formed on the 75 frame member 14. Each end of each tube 31 is closed by a cap 34 of insulating material which serves as a guide for its plunger 26 and also as a fixed abutment for the adjacent spring 29 as stated. Each cap 34 is retained by clamp plates 35 which are attached by screws 36 to the supporting clamp 32. Between the carbon piles are inserted deflecting plates 64 for the purpose of preventing a current of heated air from the lower piles from playing directly upon the piles above. Deflecting plates 64 are shown as attached by screws 65 to the frame 14.

The equalizing levers 27 shown at the left hand ends of the piles, Fig. 1, are mounted upon knife edges 27¹ carried by insulating tube 37 while the equalizing lever 27 at the right hand ends of piles 2^b and 2^c is mounted upon knife edge 27¹ carried by insulating tube 42, which tube also supports the terminal blocks 28.

Insulating tube 37 is supported by pivots 38 from a rocking member 39 which is pivoted at 40 to the frame 14. The insulating tube 42 is supported by pivots 38¹ from a 100 rocking member 39¹ which is pivoted at 40¹ to frame 14, the members 38, 39 and 40 being similar to the members 38¹, 39¹ and 40¹. Set screws indicated at 41 serve to lock the pivot pins 38, 38¹, 40 and 40¹, in the rocking members and frame.

The insulating tube 37 is actuated from the swinging armature 52, subsequently to be described, by a push rod 43, while the insulating tube 42 is similarly actuated by a 110 pull rod 44. The latter is interrupted electrically by an insulating joint 45 to insulate this mechanism from the knife edge support on tube 42 to which pull rod 44 is attached at its right hand end.

Pull rod 44, near its left hand end, referring to Fig. 1, passes freely through a bushed opening in insulating tube 37 as indicated and thus serves to maintain the two insulating tubes aligned in parallel planes so that the faces of the equalizing levers 27 will be kept perpendicular to the plungers 26 which they engage.

The actuating rods 43 and 44 are pivotally connected at their left hand ends to 125 links 46 and 47. These links, as is shown at the left hand portion of Fig. 1, are hinged at their left hand ends to opposite ends of a link 48, which serves to maintain links 46 and 47 parallel. Links 46 and 47 have 130

notches 49 formed therein which are adapted to engage knife edges 50 attached to shaft 51, (see Fig. 2). An armature 52 is also mounted on shaft 51, this armature being adapted to swing between poles formed in the cores 53 of the regulating coils 4¹, 4¹. The armature and cores, together with a base member 54 formed integral with the frame 14, constitute a magnetic circuit upon which the coils 4¹ are placed.

When coils 4¹ are energized, the armature 52 tends to swing into the plane of the two cores 53. A spring 55 is provided to oppose this tendency, (see Fig. 1), this spring being attached at its right hand end to stud 56 and connected by means of rod 57, turn buckle 58 and the eye 59 to a post 60 attached to armature 52. The armature may be provided with copper bands 61 surrounding the end portions thereof and tending to damp out oscillations of the armature. A pin 62 projected through an opening in the yoke member 63 serves to limit the movement of the armature 52.

The parts are shown in the position assumed when they are de-energized. If a current is supplied by the incoming wires to the terminal 23 at any potential higher than that for which the regulator is adjusted, the armature 52 will move towards alignment with the plane of the cores 53. In so doing it will partially release the pressure exerted by the knife edges 50 of shaft 51 against notches 49 in links 46 and 47, the movement of armature 52 towards alignment with cores 53 being opposed by spring 55. When pressure of knife edges 50 on seats 49 is thus partially released, the push of rod 43 against tube 37 and the pull of rod 44 upon tube 42 will be somewhat decreased and accordingly the pressure of tubes 37 and 42 upon the ends of the carbon piles, exerted through levers 27 and terminal blocks 28 and plungers 26, will be correspondingly decreased. The carbon piles will accordingly be permitted to expand somewhat in both directions and to partially relieve themselves of pressure. Throughout this releasing movement equality of pressure will be maintained at both ends of the piles because of the fact that an equalizing lever 27 serves to maintain equality of pressure as between each pair of adjacent piles. Furthermore the equalized pressure will be substantially maintained without any sliding of any pile as a whole through its containing tube, provided that the expansion of all piles at similar pressures is similar. Thus the maximum pressure that can exist between the carbons in any pile when the ends have been wholly relieved of pressure is the slight force required to slide the carbons from the central portion of any pile towards either end thereof during the expansion of the pile.

Such an arrangement is of importance in

cases in which the utilization of the greatest possible potential drop in the carbon piles is required, since the limiting resistance value of any carbon pile is determined by the internal pressure required between discs 70 to slide the discs along their support during the slight expansive movement of release.

Equilibrium will be restored when the releasing movement referred to has proceeded to such a point that the resistance of the carbon piles reduces the voltage available across the circuit of the coils 4¹ to normal. If now a lamp load, such as one of the lamp circuits shown in Fig. 10, is turned on in 80 one of the circuits connected to the posts 22, the corresponding relay 7^a or 7^b etc., will close, connecting the middle point of the lamp circuit by means of bus connection 21¹ to the circuit regulated by the carbon piles. 85 If the supply of voltage is less than that for which the resistor 1 are adapted, the current received by the connected lamp circuit through its own particular resistor 1 will be less than normal. The deficiency will be 90 supplied by the circuit through the carbon piles which will be accordingly readjusted as required for maintaining normal voltage under the modified condition. When any other lamp circuits are turned on the operation is, of course, the same, any deficiency of current supplied through the fixed resistors 1 being supplied by the circuit through the carbon piles in the manner described in connection with the diagram Fig. 10.

The circuits through the carbon piles, it will be noted, extends from post 24 through terminal block 28 connected therewith, pressure head or plunger 26 and carbon pile 2^A, through equalizing lever 27 at the left to pile 2^B, through the latter, through equalizing lever 27 at the right to pile 2^C, through the latter, through the equalizing lever 27 at the left to pile 2^D, through the latter, and the terminal block 28 at the right and thence to post 25.

While I have described the invention in its preferred form in great detail, it will be understood that the invention is not limited to such form or details, since many changes may be made and the invention embodied in widely different forms without departure from the spirit and scope thereof in its broader aspects, and various features of the invention may be used without using others.

I claim—

1. An electrical system having in combination a source of variable voltage, electric translating means connected to be supplied by said source, means for regulating the energy supplied by the source to the translating means comprising a variable resistance composed of a plurality of contacting electrodes and a fixed resistance in parallel 130

therewith, both being in series with the translating means, a coil responsive to certain electrical variations in the system for controlling said regulating means and a resistance in shunt to said coil, said last mentioned resistance having a constant current characteristic.

2. An electrical system having in combination a source of variable voltage, electric translating means connected to be supplied by said source, means for regulating the energy supplied by the source to the translating means comprising a variable resistance composed of a plurality of contacting electrodes and a fixed resistance in parallel therewith, both being in series with the translating means, a coil responsive to voltage variations across the translating means for controlling said regulating means and a resistance in shunt to said coil, said last mentioned resistance having a constant current characteristic.

3. An electrical system having in combination a source of variable voltage, a plurality of translating means connected to be supplied thereby, a variable resistance composed of a plurality of contacting electrodes in series with the translating means, a coil responsive to certain electrical variations in the system for controlling said variable resistance, a plurality of fixed resistances and means for connecting one or more of said fixed resistances in shunt to said variable resistance depending upon the load taken by the translating devices.

4. An electrical system having in combination a source of variable voltage, a plurality of translating means connected to be supplied thereby, a variable resistance composed of a plurality of contacting electrodes in series with the translating means, a coil responsive to certain electrical variations in the system for controlling said variable resistance, a plurality of fixed resistances and means for connecting one or more of said fixed resistances in shunt to said variable resistance depending upon the load taken by the translating devices, said last mentioned means comprising switches operating to connect the fixed resistances in shunt to the variable resistance responsive to certain variations in current supplied to the translating means.

5. An electrical system having in combination, a source of variable voltage, a plurality of translating devices connected to be supplied thereby in parallel with one another, a variable resistance composed of a plurality of contacting electrodes connected in series with the translating devices for regulating the energy supplied thereto, fixed resistance means adapted to be connected in shunt to said variable resistance and electroresponsive means controlling the connection of different amounts of said fixed resistance

in shunt to said variable resistance responsive to certain variations in load taken by said translating devices.

6. An electrical system having in combination, a source of variable voltage, a plurality of translating devices connected to be supplied thereby in parallel with one another, a variable resistance composed of a plurality of contacting electrodes connected in series with the translating devices for regulating the energy supplied thereto, fixed resistance means adapted to be connected in shunt to said variable resistance and electroresponsive means controlling the connection of different amounts of said fixed resistances in shunt to said variable resistance responsive to certain variations in load taken by said translating devices, and a coil responsive to voltage changes across the translating devices for controlling the operation of said variable resistance. 70 75 80 85 90 95

7. An electrical system having in combination, a source of variable voltage, a plurality of translating devices connected to be supplied thereby in parallel with one another, a variable resistance composed of a plurality of contacting electrodes connected in series with the translating devices for regulating the energy supplied thereto, fixed resistance means adapted to be connected in shunt to said variable resistance and electroresponsive means controlling the connection of different amounts of said fixed resistance in shunt to said variable resistance responsive to certain variations in load taken by said translating devices, and a coil responsive to voltage changes across the translating devices for controlling the operation of said variable resistance. 90 95 100 105

8. An electrical system having in combination, a source of variable voltage, a plurality of lamps connected in series with one another to be supplied by said source, a carbon pile variable resistance serially connected with respect to said lamps, a resistance in shunt relation to said variable resistance, a coil controlling said variable resistance responsive to voltage variations at 110 the lamps to control the flow of current to the lamps, and a resistance in shunt relation to said coil, said last mentioned resistance having a constant current characteristic. 115

9. An electrical system having in combination, a source of variable voltage, a plurality of lamps connected in series with one another to be supplied by said source, a variable resistance composed of a plurality of contacting electrodes serially connected with 115 the lamps, a plurality of resistance elements adapted to be connected in shunt relation to the variable resistance and in series relation with the lamps, means for so connecting one or more of said resistance elements, re- 120 125

sponsive to various amounts of current taken from the source, and means for controlling said variable resistance responsive to certain electrical variations of the system to regulate the energy supplied to the lamps.

10. An electrical system of distribution having in combination a source of variable voltage, a plurality of lamp circuits connected in parallel with one another to be supplied from said source, each of said circuits having a plurality of lamps therein in series relation with one another, a variable resistance connected in series relation with said lamp circuits, a plurality of resistance elements adapted to be connected each in shunt relation to said variable resistance and in series relation with the lamp circuits, means for so connecting one or more of said resistance elements responsive to various amounts of current taken from the source, and means for controlling said variable resistance responsive to certain electrical variations of the system to regulate the energy supplied to the lamps.

11. An electrical system of distribution having in combination a source of variable voltage, a plurality of lamp circuits connected in parallel with one another to be supplied from said source, each of said circuits having a plurality of lamps therein in series relation with one another, a variable resistance connected in series relation with said lamp circuits, a plurality of resistance elements adapted to be connected each in shunt relation to said variable resistance and in series relation with the lamp circuits, means for so connecting one or more of said resistance elements responsive to various amounts of current taken from the source, and means for controlling said variable resistance responsive to certain electrical variations of the system to regulate the energy supplied to the lamps, said variable resistance comprising a carbon pile and said controlling means comprising a coil responsive to voltage variations at the lamps.

12. An electrical system of distribution having in combination a source of variable voltage, a plurality of lamp circuits connected in parallel with one another to be supplied from said source, each of said circuits having a plurality of lamps therein in series relation with one another, a variable resistance connected in series relation with said lamp circuits, a plurality of resistance elements adapted to be connected each in shunt relation to said variable resistance and in series relation with the lamp circuits, means for so connecting one or more of said resistance elements responsive to various amounts of current taken from the source, and means for controlling said variable resistance responsive to certain electrical variations of the system to regulate the energy supplied to the lamps, said variable

resistance comprising a carbon pile and said controlling means comprising a coil responsive to voltage variations at the lamps, and a resistance in shunt to said coil, said resistance having a constant current characteristic.

13. An electrical system of distribution having in combination a source of variable voltage, a plurality of lamp circuits connected in parallel with one another to be supplied from said source, each of said circuits having a plurality of lamps therein in series relation with one another, a variable resistance connected in series relation with said lamp circuits, a plurality of resistance elements adapted to be connected each in shunt relation to said variable resistance and in series relation with the lamp circuits, means for so connecting one or more of said resistance elements responsive to various amounts of current taken from the source, and means for controlling said variable resistance responsive to certain electrical variations of the system to regulate the energy supplied to the lamps, said variable resistance comprising a carbon pile and said controlling means comprising a coil responsive to voltage variations at the lamps, and a resistance in shunt to said coil, said resistance having a constant current characteristic, and a resistance in series with said coil for limiting the voltage applied thereto.

14. In an electrical system, the combination with a plurality of load circuits, of a variable resistance, a relay associated with each load circuit, and a resistor controlled thereby, to be connected in parallel with said variable resistance when the associated load circuit is energized.

15. In an electrical system, the combination with a source of variable voltage, of a plurality of load circuits connected in parallel with one another to be supplied from said source, each of said circuits having a middle point, with electric translating means on one side of said point and a fixed resistor on the other side thereof, a variable resistance, and switch means associated with each load circuit to connect the middle point thereof with said variable resistance to connect the latter in series with the translating means of said circuit and in shunt with the fixed resistor thereof.

16. In an electrical system, the combination with a source of variable voltage, of a plurality of load circuits connected in parallel with one another to be supplied from said source, each of said circuits having a middle point, with electric translating means on one side of said point and a fixed resistor on the other side thereof, a variable resistance, and automatic switch means comprising an electromagnet in each load circuit adapted to connect the middle point thereof with said variable resistance whenever said

- 5 circuit is closed, to connect said variable resistance in series with the translating means of said circuit and in shunt with the fixed resistor thereof, said variable resistance being automatically varied to furnish deficiencies of current in all connected load circuits.
- 10 17. In an electrical system, the combination with a source of variable voltage, of a plurality of load circuits connected in parallel with one another to be supplied from said source each of said circuits having a middle point, with electric translating means on one side of said point and a fixed resistor on the other side thereof, a circuit including a carbon pile and a regulating coil therefor in series therewith connected across the terminals of all of said load circuits, and a bus connection from a point on said last named circuit between said pile and coil, and extending adjacent to all of the middle points of said load circuits, each of said load circuits having an electric magnet therein adapted to connect its middle point to said bus connection whenever said load circuit is closed, to connect said carbon pile in series with the translating means of said circuit and in shunt with the fixed resistor thereof.
- 15 18. In an electric regulator, the combination of a carbon pile, and a resistance, adapted to be connected in parallel with each other, in circuit with a source of variable potential and a load, electro-magnetic means for controlling the resistance of said pile, and a circuit in shunt with said electro-magnetic means, so arranged that current variations therein are less than proportional to the voltage variations which produce them.
- 20 19. In an electric regulator, the combination of a carbon pile, a pressure head adapted to exert pressure upon and to convey electric current to one end thereof, a separate member bearing against said head, arranged to exert a varying pressure thereon and to convey electrical current thereto, and a spring arranged to maintain mechanical contact between said head and member at all times.
- 25 20. In an electric regulator, the combination of a pair of carbon piles and an insulated pressure equalizing member in mechanical and electric contact with one end of each pile to connect them electrically and to exert mechanical pressure against them.
- 30 21. In an electric regulator, the combination of four parallel carbon piles, an equalizing lever bearing against the first and second pile, at one end thereof, an equalizing lever bearing against the second and third pile at the opposite ends thereof, and an equalizing lever bearing against the third and fourth pile at the first named end thereof.
- 35 22. In an electric regulator, the combination of a plurality of carbon piles arranged parallel to each other with their axes in the same plane, and a rocking member pivoted on an axis transverse to the axes of the piles, and arranged to maintain positions always at right angles to the axes of the piles, and to swing towards and away from the adjacent ends of the piles to exert pressure on all of the same simultaneously.
- 40 23. In an electric regulator, the combination of a plurality of carbon piles, equalizing levers at opposite ends of the piles, each lever bearing against the ends of an adjacent pair of piles, movable members on which said levers are pivoted, arranged to maintain positions always at right angles to the axes of the piles, and means for controlling the movement of said members towards and away from the piles.
- 45 24. In an electric regulator, the combination of a plurality, greater than two, of carbon piles, equalizing levers at opposite ends of the piles, each lever bearing against the ends of an adjacent pair of piles, said levers being so arranged that pressure exerted at one end of a pile will be transmitted through all the piles, and means for moving the fulcrums of all the levers towards and away from the piles simultaneously.
- 50 25. In an electric regulator, the combination of a plurality of carbon piles, pressure devices bearing against opposite ends thereof, insulating members adjacent said pressure devices, one at each end of the piles, equalizing levers carried by said members, adapted to bear against certain pairs of adjacent pressure devices, terminal blocks also carried by said members, adapted to bear against certain of said pressure devices, and means for moving said members in parallel lines towards and away from said piles.
- 55 26. In an electric regulator, the combination of a plurality of carbon piles, pressure devices bearing against opposite ends thereof, insulating members adjacent said pressure devices, one at each end of the piles, extending at right angles to the axes of said piles, contact means carried by said members, adapted to engage against said pressure devices, and automatic means for moving both said insulating members towards and away from said pressure devices, simultaneously, through like distances, while maintaining said members in parallelism.
- 60 27. In an electric regulator, the combination of a plurality of parallel carbon piles, one above the other, upright insulating members, one adjacent each end of the piles, contact devices carried by said members, for engaging the ends of the piles, and a pair of members mounted on vertical hinges, one
- 65 70 75 80 85 90 95 100 105 110 115 120 125 130

of said insulating members being hingedly mounted at top and bottom to one of the same, and the other insulating member being hingedly mounted at top and bottom 5 to the other of the same.

28. In an electric regulator, the combination of a plurality of carbon piles and regulating means therefor, comprising electro-magnetic means having a pair of pole 10 pieces, an armature pivoted between said pole pieces and adapted to swing towards alignment with said pole pieces when said electro-magnetic means is energized, pressure means at opposite ends of said piles, at 15 right angles to the axes thereof, adapted to move towards and away from the same in parallel planes, and connections between said pressure means and said armature for so moving said pressure means.

29. In an electric regulator, the combination of a plurality of carbon piles and regulating means therefor, comprising electro-magnetic means having a pair of pole 20 pieces, an armature pivoted between said pole pieces and adapted to swing towards alignment with said pole pieces when said electro-magnetic means is energized, pressure means at opposite ends of said piles, at 25 right angles to the axes thereof, adapted to move towards and away from the same in parallel planes, and links connecting points on said armature on opposite sides of the pivot thereof with said pressure 30 means and arranged to move in planes parallel with the axes of said piles.

30. In an electric regulator, the combination of a resistor and regulating means therefor comprising a pair of electro-mag- 35

net coils with pole pieces and an armature pivoted between said pole pieces and adapted 40 to swing towards alignment with said pole pieces when said coils are energized, said coils being situated beyond one end of said resistor, means for applying pressure to opposite ends of said resistor, a push 45 connection between said armature and one of said pressure applying means, and a pull connection between said armature and the other pressure applying means.

31. In an electric regulator, the combination of a plurality of tubular resistors, a plurality of carbon piles connected together in series, common electro-responsive means for applying varying pressure to all of said piles, and means for electrically connecting any of said tubular resistors in parallel with said piles.

32. In an electric regulator, the combination of a plurality of tubular resistors, a plurality of carbon piles connected together in series, common electro-responsive means for applying varying pressure to all of said piles, and means for electrically connecting any of said tubular resistors in parallel with said piles, and a frame- 65 work carrying all of said resistors and piles.

33. In an electric regulator, the combination of a plurality of carbon piles, arranged one above the other and deflecting plates positioned above each pile except the 70 uppermost, to deflect heat produced by said piles from the piles above.

In testimony whereof I have signed my name to this specification.

ELI J. BLAKE.
